UNITED STATES PATENT OFFICE.

CHARLES L. PERRY, OF SCHENECTADY, NEW YORK, ASSIGNOR TO GENERAL ELECTRIC COMPANY, A CORPORATION OF NEW YORK.

ELECTRICAL SWITCH.

Application filed October 19, 1923. Serial No. 669,557.

To all whom it may concern:

Be it known that I, CHARLES L. PERRY, a citizen of the United States, residing at Schenectady, in the county of Schenectady, State of New York, have invented certain new and useful Improvements in Electrical Switches, of which the following is a specification.

My invention relates to electrical switches, and particularly to those which are adapted to interrupt a circuit in which a large current is flowing. It has for one of its objects to provide in such a switch an improved form of contact and connector which will be strong, simple and efficient in operation.

In electrical switches of the contactor type it is customary to build the switch mechanism of cast-iron or like material, and to provide low resistance contacts and connectors to carry the current passing through the switch. Heretofore these connectors have been secured to the contacts by bolts or similar means. When the connectors are connected in this manner they frequently work loose, and often the surfaces of the connected parts because of unevenness prevent a good contact being made between the parts. These conditions create resistance between the parts which will cause them to unnecessarily heat up and thereby consume power which would otherwise pass through the switch. This heating will also cause the flexible conductor to become brittle and thus impair its flexibility. In switches of small current capacity the heating of the contact and consequent loss of power will be negligible, but in switches where large current is carried the heating and loss of power due to poor contact between the parts is often considerable. To reduce this heating it is necessary to reduce the resistance of the parts and the contact resistance between the parts to a minimum. I propose to overcome this heating by providing a flexible connector or shunt having its end consolidated into a solid and rigid mass of suitable shape to form the contact. Such a construction will eliminate the contact resistance heretofore present between the connector and the contact.

When switches of the above type are used to control circuits where a large current has to be interrupted, it is customary to provide a plurality of contacts which open in succession for the purpose of breaking the arc, which is drawn as the contacts open. In my improved switch, I employ three contacts, which I shall refer to hereinafter as a main contact, an intermediate contact and an arcing contact, all of which make wiping contact in closing, are mounted on the same movable member, and open in the reverse order of their closing. The main contact is made comparatively heavy so that it can carry the current continuously and the other contacts are made small, but of sufficient size to carry the current momentarily. The intermediate and arcing contacts, being small, are cheap, easy to replace, and protect the heavy contact from burning and also prevent it from freezing in the closed position. The small contacts open to a greater distance than the main or heavy contact and thereby tend to break the arc by pulling it out to a length at which the voltage will not maintain it. The last contact to open is usually provided with a magnetic blowout which assists in disrupting the arc. To insure that the contacts open in the proper order and that the contact adjacent the magnetic blowout, or arcing contact is last to open, it is necessary to provide means which will open the other contacts before the arcing contacts open. To this end, the intermediate contact is pivotally mounted on the movable member, spring pressed toward its closing position, and is provided with a stop for limiting its movement toward the closing position and insuring its opening in point of time between that at which the main and arcing contacts open and close. It is also desirable that the contacts, and especially the intermediate contact be adjustable, so that wear of the parts and burning of the contact can be compensated for. In order to accomplish this, I make the stop for the intermediate contact adjustable so that this contact can be set in different positions as conditions require.

For a better understanding of my inven-

tion reference should be had to the following description taken in connection with the accompanying drawing in which Fig. 1 is a perspective view of the preferred form of 5 contact, made in accordance with my invention; Fig. 2 is a sectional view of the contact shown in Fig. 1; Fig. 3 is a side elevation of an electrical switch of the contactor type; and Figs. 4 and 5 are views showing 10 one manner of mounting the main contact.

Referring to Figs. 1 and 2 of the drawing, I have shown a flexible conductor comprising a plurality of strands 11, the strands at the end 10 being consolidated into 15 a substantially solid and rigid mass, making a solid end to a flexible connection. The end 10 of this conductor forms the movable contact of an electric switch and the other end of the conductor is fastened to a stationary terminal, as will be set forth more at length hereinafter. In my preferred construction, a tube or casing 12 is slipped over the end 10 of the conductor and the tube and strands contained therein are consolidated into a solid rigid mass by drop 20 forging. The casing 12 is provided with a flared end 13 which will prevent abrupt flexing of the conductor when the switch is opened and closed and thus prolong its life.

30 In Fig. 3 of the drawing, I have shown an electric switch in which the conductor above described is employed. A stationary terminal 15 is shown mounted upon the panel 14 and the end 16 of the flexible conductor 35 is secured thereto. The flexible conductor is composed of a plurality of small strands 11, of conducting material such as copper, and is adapted to flex back and forth as the switch opens and closes. The other end of 40 the flexible conductor forming the contact 10 is carried by movable member 17 and is adapted to make and break contact with a stationary contact 18.

The stationary contact 18 is supported 45 at a point adjacent the contact 10 by a current carrying stud 19 which passes through the panel 14. The movable member 17 is secured by a clevis 20 to a shaft 21, which is adapted to oscillate in response to 50 any suitable means, as for instance, an electromagnetic means. As the shaft 21 oscillates it will cause the movable contacts of the switch to make and break contact with their respective stationary contacts to control the 55 circuit in which they are connected. In addition to the main contact 10 the movable member 17 carries an intermediate contact 22 and an arcing contact 23. The main contact 10, the intermediate contact 22 and the arcing contact 23 are supported so that 60 they make wiping contacts in closing and open in the reverse order of their closing. The contacts 10, 22 and 23 are all pivoted to the movable member 17 and are spring

pressed toward their respective stationary 65 contacts so that they will make a wiping contact when the switch is closed.

Mounted upon the panel 14 adjacent the intermediate contact 22 is a stationary contact 24 and adjacent the arcing contact 23 70 is a similar stationary contact 25. Connected between the stud 19 and contact 25 is a coil 26 which acts in a well known manner to blow out the arc formed between the arcing contact 23 and 25 as the switch opens. 75 Interposed between the movable member 17 and the intermediate contact 22 is a nut or stop 27 for limiting the movement of this contact toward the closing position. It also acts to insure that the intermediate contact 80 opens and closes, in point of time, between that at which the main and arcing contacts open and close. This stop is preferably made adjustable so that the wear of the parts and the burning of this contact can be compensated for. A lock-nut 28 is provided to secure stop 27 in position when properly adjusted. The intermediate and arcing contacts 22 and 23 are provided with low 85 resistance connectors or shunts 29 and 30, respectively, for carrying the current passing 90 through said contacts.

Referring to Figs. 4 and 5 of the drawing, the main contact 10 is shown as pivotally supported on the movable member 17 by a 95 U-shaped member 31 and a hook member 32. Cooperating with the U-shaped member 31 and the hook member 32 and forming a fulcrum for said contact is a spring 33 which forces contact 10 into engagement 100 with the stationary contact 18 when the switch is in its closed position. This type of mounting permits contact 10 to tilt in any direction for the purpose of securing a good contact between the engaging surfaces. Fig. 4 shows the spring 33 extended as when the switch is open, and Fig. 5 shows the spring 33 compressed as when the 105 switch is closed.

What I claim as new and desire to secure 110 by Letters Patent of the United States, is:—

1. In an electric switch, a stationary contact, a stationary terminal, a flexible conductor comprising a plurality of strands having one end fastened to said terminal 115 and its other end forming a movable contact adapted to make contact with said stationary contact, the strands at said end forming the movable contact being consolidated into a substantially solid and rigid mass.

2. In an electric switch, a stationary contact, a stationary terminal, a flexible conductor comprising a plurality of strands having one end fastened to said terminal 120 and its other end forming a movable contact adapted to make contact with said stationary contact, the strands at said end forming the movable contact being

enclosed in a tube, the said tube and strands being consolidated into a substantially solid and rigid mass.

3. In an electric switch, a stationary contact, a stationary terminal, a flexible conductor comprising a plurality of strands having one end fastened to said terminal and its other end forming a movable contact adapted to make contact with said sta-

tionary contact, the strands at said end 10 forming the movable contact being enclosed in a tube having a flared end, the said tube and strands being consolidated into a substantially solid and rigid mass.

In witness whereof, I have hereunto set 15 my hand this 18th day of October 1923.

CHARLES L. PERRY.
